Specification for Design.

Patented Feb. 22, 1921.

Application filed May 28, 1920. Serial No. 385,077. Term of patent 14 years.

To all whom it may concern:

Be it known that I, JOHN T. JOHNSON, a citizen of the United States, residing at Akron, in the county of Summit and State of Ohio, have invented a new, original, and ornamental Design for Tires, of which the following is a specification, reference being had to the accompanying drawing, forming part thereof.

Figure 1 is a plan view and Fig. 2 a cross section on line 2—2, Fig. 1, showing my new design for a tire.

I claim:

An ornamental design for a tire, as shown.

JOHN THOMAS JOHNSON.
